FOREIGN PATENT DOCUMENTS

WO 0121034 A2 3/2001

Primary Examiner — Joseph Kukella*Assistant Examiner* — Darryl J Dardenne(74) *Attorney, Agent, or Firm* — Hanrahan Law Firm, P.A.; Benjamin M. Hanrahan(57) **CLAIM**

The ornamental design for a spoon holder, as shown and described.

DESCRIPTION

FIG. 1 is a perspective view illustrating my/our design for a spoon holder.

FIG. 2 is another perspective view thereof.

FIG. 3 is a left side view thereof.

FIG. 4 is a front view thereof.

FIG. 5 is a right side view thereof.

FIG. 6 is a rear view thereof.

FIG. 7 is a top view thereof.

FIG. 8 is a bottom view thereof.

FIG. 9 is another perspective view thereof with the lid open.

FIG. 10 is another perspective view thereof with the lid open; and,

FIG. 11 is another right side view thereof with the lid open. The broken lines shown in FIG. 10 are for the purpose of illustrating environment and form no part of the claimed design.

1 Claim, 11 Drawing Sheets(56)
